UNITED STATES PATENT OFFICE.

PHILIP F. CARROLL, OF JOLIET, ILLINOIS.

OVEN.

1,029,589.

Specification of Letters Patent. Patented June 18, 1912.

Application filed May 16, 1907. Serial No. 374,030.

To all whom it may concern:

Be it known that I, PHILIP F. CARROLL, citizen of the United States, residing at Joliet, in the county of Will and State of Illinois, have invented certain new and useful Improvements in Ovens, of which the following is a specification.

My invention relates to ovens and especially to that class of bakers' ovens having a rotary appliance for handling the product and commonly termed reel ovens.

The chief objects of my invention are to provide an oven of the type designated that will facilitate the handling of the material inserted therein and the removal of the finished product; to produce an oven of such design that the heat will be easily distributed, and to furnish the usual non-conducting material to prevent radiation and conversion of the heat and thus maintain a uniform degree of temperature throughout the structure.

Further objects of my improved oven are to furnish convenient appliances for regulating the necessary valves and dampers, and to provide the main feed and discharge opening with a balanced door that will retain its position when opened or closed.

I accomplish the above and other minor results by the apparatus illustrated in the accompanying drawings which form a part of this specification, and in which:

Figure 1 is a sectional elevation of an oven embodying my improvements taken on a longitudinal median plane; Fig. 2 is a similar view taken on a transverse plane, the reel having been removed; Fig. 3 is a sectional view on a horizontal plane cutting the fire box, and Fig. 4 is a horizontal section through the upper portion of the oven, the flues being shown in full.

Referring to the drawings in detail the numerals 5 and 6 indicate the front and rear walls, respectively, and 7 the side walls of a rectangular oven preferably constructed of brick, which present the desirable physical property of heat non-conductivity producing a durable structure calculated to retain the heat for a considerable time at a uniform temperature.

A fire box 8 is located in the center of the front and furnished with grate bars 9, a door 10 and an ash pit 11. A horizontal partition 12 extends over the whole area of the structure and forms a floor for the heating chamber 13 in which is located the reel.

This is hung upon a shaft 14 journaled in the side walls of the oven and arranged for the application of power in any convenient manner. The reel may be of any of the well known forms, the structure shown consisting of two sets of radiating arms 15 only one of which is shown secured to flanged boxes 16 and connected by ties 17. The extremities of the arms are connected by rods 18 upon which are hung the baking trays 19.

The baking chamber is provided with the usual feed and discharge opening 20 for which is provided a closure 21 furnished with a counterbalance 22. At the rear of the fire box is the main flue 23 which extends horizontally back to the wall 6 and communicates with a chimney flue 24, the opening being closed by a damper 25 which is manipulated by a cable or chain 26 extending through a pipe 27 to the front of the oven. Extending parallel with the side walls of the oven are partitions 28, 29, which are duplicated upon each side to form passages or flues 30, 31, which communicate with each other and with the central flue by openings 32, 32^a. At the rear ends the outside flues 31 communicate with vertical flues 33 preferably formed of brick and extending into the baking chamber 13. These flues are directly connected at their upper ends with a series of flues 34, 34^a, rectangular in cross section preferably formed of sheet metal and spanning the baking chamber in a series of parallel arches. There are four of these arches, the two lying externally being in communication on the side of the oven opposite to the said flues 33, through a breeching 35 with the adjacent middle arch, 36 and the latter in turn communicate at 36 with each other, and finally open into the chimney flue 24 through an orifice 37 which is controlled by a damper 38 which has suitable operative connection with a handle 39, placed at the front of the oven for convenience. This arching arrangement of the flues which are thus distributed approximately over the whole area of the baking chamber insures a complete and uniform distribution of the heat and as the arched roof thus formed is brought into close relationship with the upper half of the reel, the heat will be applied in the most desirable and economical manner. As a still further means of confining and as a result economizing the heat a covering of non-conduct-

ing material 40 is supplied to the roof of the oven. This may be constructed of a single layer or of superimposed layers of different materials and asbestos or other 5 cellular substance may be employed for that purpose.

Having thus described my invention what I claim as new and desire to secure by Letters Patent, is:—

10 A baking oven, including a baking chamber, means for heating said chamber and a chimney, a series of inner and outer flues for the products of combustion, said flues

being arranged in a semicircular arch spanning said chamber from front to rear, 15 the inner flues communicating with each other at one end and with the outer flues at the other end, and one of said inner flues communicating with said chimney.

In testimony whereof I affix my signature 20 in the presence of two witnesses.

PHILIP F. CARROLL.
